UNITED STATES PATENT OFFICE

NEAL W. DORMAN, OF TOLEDO, OHIO, ASSIGNOR TO THE TOLEDO MACHINE & TOOL COMPANY, OF TOLEDO, OHIO, A CORPORATION OF OHIO

HYDRAULIC CONTROL MECHANISM

Application filed June 1, 1931. Serial No. 541,173.

This invention relates to hydraulic control mechanism which is adapted to be operated intermittently from a continuously operating pump and without the interposition of a pressure accumulator. It is of special utility in controlling the operation of the clutch on a large power press or in controlling other machines which are of such size and power that manual control is an arduous task.

10 One of the objects of the invention is to provide a hydraulic control device in which there is substantially no pressure in the line and no power consumed except when the machine is being operated, although the pump 15 normally operates continuously.

Another important object is to promote safety by providing a control device whereby the machine is automatically brought to a stop by mechanical means, even if there is 20 no pressure accumulator connected with the control device and the pump may have ceased to operate.

The specific construction of the invention in its preferred form and the advantages 25 resulting therefrom will be more particularly described in the accompanying drawing, in which—

Figure 1 is a diagrammatic view illustrating the control system;

30 Figure 2 is an enlarged central longitudinal section through the cylinder and valve mechanism;

Figure 3 is a section taken substantially on the line 3—3 of Fig. 2;

35 Figure 4 is a section taken on the line 4—4 of Fig. 3; and

Figure 5 is a section taken on the line 5—5 of Fig. 3, but with the valve in an intermediate position.

40 The hydraulic control mechanism to which the invention relates includes a housing 7 formed with a bracket 8 by which it may be attached to the machine to be controlled. The fluid pressure is developed by a pump 45

9 which may be of any suitable type and is adapted to be continuously driven. The fluid, which is preferably oil, is drawn from a storage tank 10 through a pipe 11 and is forced under pressure through the pipe 12

50 to the control mechanism. The fluid is re-

turned to the tank 10 through the pipe 13. Pipes 12 and 13 are also connected by a by-pass 14 in which is a relief valve 15 which opens at a predetermined pressure to prevent overloading the system.

55 The housing 7 is formed with a cylinder 16 in which a piston 17 is mounted for reciprocation. The cylinder 16 is provided with an extension 18 through which the stem 19 of the piston extends and which contains a spring 20 for acting on the piston 17 in opposition to the fluid pressure through the cylinder and for returning the piston to the end of the cylinder when the fluid pressure is relieved. The piston is provided with a cup 60 21 or other suitable means to prevent leakage of the fluid. The outer end of the piston rod 19 may be connected to a bell crank 22 or to any other mechanical element for transmitting power to the clutch or other mechanism 65 to be controlled.

70 The cylinder 16 is formed on one side with a valve housing 23 into which a port 24 leads from the inner end of the cylinder. A seat 25 is secured in the bottom of the housing 23 and has a port 26 in registry with the port 24. A valve 27 is disposed within the housing 23 between the seat 25 and a cap 28 which is secured to the housing. The valve is secured on a spindle 29 which is mounted for rocking movement in the seat 25 and cap 28 and which is provided with a crank arm 30 adapted to be connected with a suitable tripping device for shifting the valve to render the control mechanism effective or to release 80 the same.

85 The cap 28 is formed internally with an annular chamber 31 having a port 32 connected with the pressure line 12. The seat 25 is formed with a cavity 33 connected through a port 34 to the return or exhaust pipe 13. A dowel pin 35 is mounted in the housing 7 and extends through the seat 25 into an arcuate recess 36 in the valve 27 concentric with the axis 29. This pin limits the rocking movement of the valve in either direction. The valve 27 has two diametrically opposed ports 37 and 38 therethrough and also has an arcuate recess 39.

90 The valve 27 is shown in Fig. 5 in an inter-

mediate position. When the valve is rocked to bring the port 37 in registry with the port 26, pressure will be admitted from the line 12 through the chamber 31, ports 37 and 26 to the cylinder so that the piston will be moved in opposition to the spring 20 to actuate the mechanism which engages the clutch or effects any other function for which the hydraulic control is used. When the valve 10 is rocked to bring the port 38 into communication with the cavity 33, the arcuate recess will then be in position to connect the port 26 with the cavity 33. At the same time the pressure line 12 and the port 37 will be cut 15 off from the port 26. With the valve in this position, which may be termed its normal position, the fluid from the cylinder 16 will be drained through port 26, recess 39, cavity 33 and port 34 into the return line 13. Also, 20 the fluid which is being pumped into the line 12 will pass freely through chamber 31, port 38, cavity 33 and port 34 directly into the return line 13 so that no pressure will be developed and practically no power will be 25 consumed by the operation of the pump.

When the valve is in normal position as above described, with the ports 32 and 26 both communicating with the return or exhaust line 13, the piston 17 will be held by the 30 spring 20 in the position shown in Figs. 1 and 2, and it is to be understood that the clutch or other member controlled by the piston is in inactive position. When the valve is rocked, either automatically or manually 35 through the medium of the crank arm 30, to its other extreme position, fluid pressure will act on the piston 17 to overcome the pressure of the spring 20 and to shift the controlled member to active position. In case 40 the pump becomes inoperative; however, or for any other reason the pressure fails, the controlled member will always be returned to inactive position as soon as the valve is returned to its normal position. This feature 45 is of the utmost importance as a safety device.

While the invention is primarily intended for use in controlling the clutch of a power press, it is also adapted for other uses and 50 its construction may be considerably modified without departing from the essential scope of the invention as defined in the appended claims.

What I claim is:

55 1. In combination, a valve housing, a seat within the housing, a rotatable valve on said seat, said housing including a cap holding the valve on its seat and formed with an annular chamber therein provided with a pressure 60 supply port, said seat having a pressure delivery port therethrough and also an exhaust port, said valve having two holes therethrough and a channel in the base adjacent the seat, said channel establishing unrestricted communication between the delivery port

and the exhaust port and one of the holes being in unrestricted communication with the exhaust port in one position of the valve, said channel being idle and the other hole being in communication with the delivery 70 port in another position of the valve.

2. In combination, a valve housing, a seat within said housing having a pressure delivery port and an exhaust port, a rotatable valve on said seat having two holes therethrough, a pressure supply chamber, said valve being movable to one position in which one of said holes is closed by the seat and the other of said holes affords communication between said pressure supply chamber 75 and said delivery port, said valve being movable to another position in which the first of said holes affords direct communication between said supply chamber and said exhaust port while the second hole is closed by the seat, said valve having a channel which, in the last described position of the valve affords communication between said delivery port and the exhaust port.

3. In combination, a valve housing, a seat within said housing having a pressure delivery port and an exhaust port, a rotatable valve on said seat having two holes therethrough in such position that the valve may be selectively moved to bring one hole in registry 90 with the pressure delivery port while the other hole is closed by the seat, or to bring said other hole in registry with the exhaust port while the first is closed by the seat, a pressure supply chamber on the side of the 100 valve opposite to said seat and in constant communication with both of said holes, said valve having a channel affording communication between said pressure delivery port and said exhaust port while the valve is in position to connect the pressure supply chamber 105 with the exhaust port.

In testimony whereof I have hereunto signed my name to this specification.
